US00D947894S

(12) **United States Design Patent** (10) **Patent No.:** **US D947,894 S**
Ryu (45) **Date of Patent:** **** Apr. 5, 2022**

(54) **DISPLAY SCREEN OR PORTION THEREOF WITH GRAPHICAL USER INTERFACE**

(71) Applicant: **INTUIT INC.**, Mountain View, CA (US)

(72) Inventor: **Jung Yeon Ryu**, Mountain View, CA (US)

(73) Assignee: **INTUIT INC.**, Mountain View, CA (US)

(**) Term: **15 Years**

(21) Appl. No.: **29/766,923**

(22) Filed: **Jan. 19, 2021**

Related U.S. Application Data

(62) Division of application No. 29/645,455, filed on Apr. 26, 2018, now abandoned.

(57) **CLAIM**

The ornamental design for a display screen or portion thereof with graphical user interface, as shown and described.

DESCRIPTION

FIG. 1 is a front view of a display screen or portion thereof with graphical user interface showing my new design; and, FIG. 2 is a front view of a second embodiment thereof. The outermost broken lines in the Figures show a display screen or portion thereof and form no part of the claimed design.
